COMBINATION PADLOCK

Frederic K. Heyer, Stamford, Conn., assignor to
The Yale & Towne Manufacturing Company,
Stamford, Conn., a corporation of Connecticut

Application November 27, 1943, Serial No. 511,903

26-Claims. (Cl. 70—21)

This invention relates to padlocks and more particularly to padlocks of the combination tumbler type. Even more particularly, my invention relates to combination padlocks in which the locking mechanism may be actuated under the control of a key as well as through the combination tumblers.

As one feature of my invention, I utilize a novel form of fence and bolt combination with the fence being movable by the combination tumblers for rotating the bolt. As a further feature of the invention, the bolt is rotatable under the control of a key independently of the combination tumblers, and preferably independently of the fence.

A still further feature of my invention resides in the means for controlling the fence, and for effecting its movement to disperse the combination of the tumblers.

I have thus described the more important features of my invention in order that my contribution to the art may be more readily understood. There are certain additional features of my invention that will be better understood after a reading of the specification that follows. I shall of course lay claim to those additional features in addition to the features hereinafter set forth.

Referring now to the drawings,

Fig. 1 is a perspective view of a padlock embodying my invention and showing a shackle in locked position and also in released position, the released position being illustrated in dash and dotted lines.

Fig. 2 is a vertical section through the padlock of Fig. 1.

Fig. 3 is a view of the back of the dial assembly.

Figs. 4 and 5 are respectively sections along lines 4—4 and 5—5 of Fig. 2.

Fig. 6 is a view similar to Fig. 5 illustrating the rotation of the bolt by the tumblers.

Fig. 7 is a view of the parts of Fig. 6 illustrating the action of the disperser.

Fig. 8 is a view taken along lines 8—8 of Fig. 2 but showing the parts when the fence has moved into the tumbler gatings.

Figs. 9 and 10 are views similar to Fig. 8 showing the parts in different positions.

Fig. 11 is a view similar to Fig. 5 but illustrating the key rotation of the bolt to release position.

Fig. 12 is a perspective view of the bolt and fence in assembled relation.

Fig. 13 is a view of the back plate of the lock 55

on which is mounted the disperser and a control lug.

Figs. 14 and 15 illustrate the relationship of the fence and bolt relatively to the shackle.

Referring now more particularly to the drawings, and especially Figures 1, 2 and 3, the casing of my padlock is designated generally by reference numeral 10 and the shackle by reference numeral 11. The dial of the padlock, which in my invention preferably carries the numerals of the combination, is designated by reference numeral 12. The construction of the dial is not part of my invention and is well illustrated in the Brauning Patent No. 2,150,660 of April 18, 1939.

For the purposes of my invention it is merely necessary to indicate that a key plug 13 is mounted within the dial 12 and is normally locked for rotation therewith by a series of tumblers that are not shown. When the key plug 13 rotates with the dial 12, this rotation is free relatively to a clutch member 14 that is in keyed relation at 15 to the post 16 of the rotary bolt 17 of my lock. When the key plug 13 is rotated relatively to the dial 12, the dial is locked or clutched to the clutch member 14 for rotating that clutch member and the bolt 17. Under the circumstances just described, the dial 12 and the bolt 17 will of course rotate as a single unit. It is thus apparent that whereas the dial 12 normally rotates freely of the bolt 17, it may be coupled to the bolt 17 at will for rotating that bolt.

Rotatable with the dial 12 is a tumbler operating member 20 from which extends a pin 21 as best shown in Fig. 3. The pin 21 fits into the gating 22 of the uppermost tumbler of the series of tumblers 23, and thereby rotates the tumblers to align their gatings, all as will be appreciated by those skilled in the art. The tumbler operating member 20 is itself formed with a gating 24, this gating being used in the same manner as are the gatings 22 of the several tumblers 23.

The tumblers 23 are carried by a mounting member 25 that fits about the post 16 of the bolt 17 and is held against rotation on the post by an arm 26 extending therefrom. The arm 26 is adapted to fit into a slot 27 of what I term the base member 28 of the padlock. It is of course obvious that the tumblers are adapted to rotate about the mounting member 25 and to have their gatings 22 aligned in the usual manner well known in the art upon rotation of the dial 12 and its operating member 20.

The padlock casing 10 is fabricated from the base member 28 and a base plate 29 held together

by a sheet metal scalp 30 that also holds in position a front plate 31. Lying against the base plate 29, and between it and the base member 28, is what I term a back plate 32, probably best shown in perspective in Fig. 13. The back plate 32 carries a control lug 33 and a disperser 34. The disperser 34 is pivoted through the pin 35 relatively to the back plate 32 as is probably best illustrated in Figs. 2 and 8. Through a spring 36 the disperser 34 is urged in a clockwise direction in Figs. 6, 7, 11 and 13 and in a counter-clockwise direction in Figs. 8, 9 and 10. The back plate 32 is of course held against rotation and for all intents and purposes may be considered an integral part of the base plate 29 and the base member 28.

The bolt 17 of my lock on which is formed the post 16, is best illustrated in Figs. 12, 14 and 15. There it will be noted that the bolt 17 is formed with a flange 40 that extends laterally from the circular plate portion 41 of the bolt. The post 16 extends through the plate 41 of the bolt and outwardly at 42 in the form of a slotted pin. The pin 42 is adapted to be inserted through the bore 43 of the back plate 32 as probably best shown in Fig. 2, and a torsion spring 44 is adapted to have one end thereof fitted into the slot 42a of the pin 42, while its other end is secured to a pin 45 forming an integral part of the back plate 32. It is the function of the spring 44 to rotate the bolt 17 into its locked relation relatively to the shackle 11, illustrated in Fig. 14. There, it will be noted that the flange 40 of the bolt 17 is in locking relation to the slots 11a of the shackle 11.

The flange 40 is scalloped at 46 and 47 so that when the bolt 17 is rotated to the position of Fig. 15 against the pressure of spring 44, the shackle is released for outward movement. This outward movement is imparted to the shackle, as best shown in Fig. 4, by a spring pressed 40 plunger 48 urged outwardly by the spring 49 and limited in its outward movement by a pin 50 moving in a slot 51 of the plunger. The outward movement of the shackle 11 is limited by a pin 52 fitting in a slot 53 in one leg of the shackle and adapted to impinge against the shoulder 54 of the said leg, all as will be well understood by those skilled in the art.

The plate portion 41 of the bolt 17 is formed with an arcuate slot 55 terminating in a transverse slot 56. It is formed with a further rather arcuate slot 57, the form of which is made complex by an extension 58 that is an integral part of the plate portion 41 of the bolt 17. As illustrated in Figs. 12, 14 and 15, a fence 60 is adapted for sliding and rotary motion relatively to the bolt 17, and is held against the inside surface of the plate 41 of the bolt 17 by a retainer ring 61 notched at 62. The fence 60 has a small substantially elliptical form of central opening 63 cooperating with a disc-like extension 64 of the plate 41 of the bolt whereby it is guided for rotary and sliding motion relatively to the bolt, all as illustrated in Figs. 14 and 15.

The back of the fence 60 carries a fixed pin 65 that is adapted to fit in the arcuate slot 55 and in the transverse extension 56 thereof. The fence 60 is further equipped with a disperser lug 66 that is adapted to ride in the complex slot 57 formed in the bolt plate 41. In the assembly of the parts, the back plate 32, as was indicated earlier, forms an integral part, in effect, of the padlock casing. The bolt 17 is applied to the backplate 32 with the lug 33 of the back plate entering the arcuate slot 55 and assuming the 75

position relatively to the fence and pin 65 that is illustrated in Fig. 5. Simultaneously, the disperser 34 enters the complex slot 57 and assumes the position illustrated in Fig. 5.

The fence 60 is formed with a fence post 68 adapted for entry into the several gatings 22 of the tumblers and also into the gating 24 of the tumbler operator 20. The fence post 68 has pressing thereagainst a leaf spring 69 secured at 70 to the base member 28. It is of course readily perceived from Fig. 4, that the leaf spring 69 will continuously urge the fence post 68 towards the tumbler gatings and thereby will urge the fence upwardly from its position of Figs. 4 and 12, that being the position of the parts when the shackle is locked and the fence post 68 is against the tumbler peripheries. In Fig. 8, I show the parts of Fig. 12 when the fence post 68 is in the aligned gatings of the tumblers.

I shall now describe the operation of my invention. With the parts in the position of Figs. 4 and 5, the shackle is of course locked because the bolt 17 is in that relation to the shackle illustrated in Fig. 14. It is obvious also that the fence 60 is held against rotation. Thus, the pin 65 of the fence is against the lug 33 of the back plate 32 thereby preventing counter-clockwise rotation of the fence. Clockwise rotation of the fence is prevented through the disperser lug 66 abutting the disperser 34. Therefore, it may be said that when the fence 60 is in its locked position relatively to the tumblers, it is prevented from rotating by the lug 33 and the disperser 34 secured on the fixed back plate 32.

However, the complex slot 57 of the plate portion 41 of the bolt 17 will be so disposed relatively to the disperser 34 and the disperser lug 66 as to permit rotation of the bolt relatively to those parts. Similarly, the arcuate slot 55 is in such relation to the lug 33 and the pin 65 of the fence 60 as to allow rotation of the bolt 17 relatively to those parts. Therefore, with the elements of the lock in the position of Figs. 4 and 5, operation of the key plug 13 for clutching the dial 12 to the bolt post 16 will allow integral rotation of the dial 12 and the bolt 17 from the position of Fig. 5 against the pressure of the torsion spring 44. This key controlled rotation is well illustrated in Fig. 11. In that figure it will be noted that the bolt has rotated to its position of Fig. 15 relatively to the shackle 11 thereby releasing the shackle. The slots 55 and 57 are now positioned in approximately limit relation to the lug 33 of the back plate 32 and the disperser lug 66 of the fence 60, thereby limiting the rotation of the bolt 17. It will be seen that there has been absolutely no rotation of the fence 60 and that all movement of the bolt 17 has been independent of the tumblers.

With the parts in the position of Figs. 4 and 5, should it be desired to release the shackle through the medium of the combination tumblers 23, the dial 12 will be operated to position the operator 20 and tumblers 23 with their gatings opposite the fence post 68. The fence will then move under the influence of the spring 69 to bring the pin 65 into the upper portion of the transverse slot 56 of the bolt plate 41. Simultaneously, the disperser lug 66 will be carried opposite the surface 58a of the part 58 of the bolt and away from abutting relation to the end of the disperser 34. This is the position of the parts in Fig. 8.

It is obvious, that rotation of the tumblers will now effect the rotation of the fence 60. The fence

60 will of course rotate with the bolt through the action of the pin 65 lying in the end of the transverse slot 56. The parts will through rotation reach their release position of Figs. 6 and 9, at which point the bolt 17 is in that relation to the shackle that is illustrated in Fig. 15. It will be noted that in these figures the end of the slot 55 has moved opposite the lug 33 extending from the back plate 32. It will also be noted that in this position of the parts the disperser lug 66 10 has moved beyond the disperser 34, it being apparent that while moving to the position of Fig. 6 the disperser lug depressed the disperser 34 against the pressure of its spring 36. Fig. 9 illustrates the back of Fig. 6 and shows quite 15 clearly the relation between the disperser lug 66 and the disperser 34. The parts will be held in the position of Figs. 6 and 9 by the longer shackle leg lying within the scalloped portion 47 of the bolt flange 40. The bolt rotating spring 44 will of course tend to rotate the parts back to the position of Fig. 5 but will be held against such action by the shackle.

When the shackle is re-inserted into the padlock casing, the bolt 17 will be rotated by the spring 44 from the position of Figs. 6 and 9 toward the position of Figs. 7 and 10. Glancing now at Fig. 10 which shows the back of the bolt when the parts are in the position of Fig. 7, the disperser lug 66 is now below the disperser 34 being moved to that position against the pressure of the fence spring 69. In the position of the parts in Figs. 7 and 10, the fence post 68 has of course moved out of the tumbler gatings and thereafter the fence 60 rotates with the bolt 17 beyond the position of Figs. 7 and 10 relatively to the tumblers, effectively dispersing the combination. Naturally, when the parts reach the position of Fig. 5 the fence returns again to its locked relation as determined by the lug 33 and the disperser 34, as well as by the peripheries of the tumblers.

I believe that the operation and construction of my invention will now be apparent to those skilled in the art.

I now claim:

1. In a lock of the class described, a rotatable bolt, a post extending from said bolt in its axis of rotation, a series of tumblers mounted for rotation about said post, means for rotating said tumblers, a fence mounted for sliding movement relatively to said bolt, and means locking said bolt to said fence when said fence is moved to release position through the alignment of the gatings of said tumblers, said fence when out of said tumbler gatings allowing free rotation of said bolt relatively thereto.

2. In a lock of the class described, a rotatable bolt, a post extending from said bolt in its axis of rotation, a series of tumblers mounted for rotation about said post, a knob for rotating said tumblers, a fence mounted for sliding and rotary movement relative to said bolt, and means locking said bolt to said fence when said fence is moved to release position through the alignment of the gatings of said tumblers.

3. In a lock of the class described, a rotatable bolt, a series of rotatable tumblers having gatings, means for rotating said tumblers to align said gatings, a fence spring pressed toward said gatings whereby to enter said gatings when they are aligned, and means whereby said fence when in said gatings is locked for rotation with said bolt, said fence when out of said gatings being free of said bolt whereby said bolt is then rotatable independently of said fence.

4. In a lock of the class described, a rotatable bolt, a series of rotatable tumblers having gatings, means for rotating said tumblers to align said gatings, a fence adapted to enter said gatings when they are aligned, and means whereby said fence when in said gatings is locked for rotation with said bolt, said fence when out of said gatings being free of said bolt whereby said bolt is then rotatable independently of said fence.

5. In a lock of the class described, a rotatable bolt, a spring pressing said bolt into a locking position, a series of rotatable tumblers having gatings, means for rotating said tumblers to align said gatings, a fence spring pressed toward said gatings whereby to enter said gatings when they are aligned, and means whereby said fence when in said gatings is locked for rotation with said bolt, said fence when out of said gatings being free of said bolt whereby said bolt is then rotatable independently of said fence and against the pressure of said bolt pressing spring.

6. In a lock of the class described, a rotatable bolt, a spring pressing said bolt into a locking position, a series of rotatable tumblers having gatings, means for rotating said tumblers to align said gatings, a fence spring pressed toward said gatings whereby to enter said gatings when they are aligned, means whereby said fence when in said gatings is locked for rotation with said bolt, and means for locking said fence against rotation when it is positioned out of said gatings, said fence when out of said gatings being free of said bolt whereby said bolt is then rotatable independently of said fence and against the pressure of said bolt pressing spring.

7. In a lock of the class described, a rotatable bolt, a post extending from said bolt in its axis of rotation, a series of tumblers mounted for rotation about said post and having gatings, means 40 for rotating said tumblers, a fence mounted for sliding movement relatively to said bolt into and out of said gatings, means locking said bolt to said fence when said fence is moved to release position through the alignment of the gatings 45 of said tumblers, said fence when out of said tumbler gatings allowing free rotation of said bolt relatively thereto, and means for locking said fence against rotation when it is positioned out of said gatings.

8. In a lock of the class described, a rotatable bolt, a series of rotatable tumblers having gatings, means for rotating said tumblers to align said gatings, a fence spring pressed toward said gatings whereby to enter said gatings when they are aligned, means whereby said fence when in said gatings is locked for rotation with said bolt, said fence when out of said gatings being free of said bolt whereby said bolt is then rotatable independently of said fence, and means for locking said fence against rotation when it is positioned out of said gatings.

9. In a lock of the class described, a rotatable bolt, a series of tumblers formed with gatings and rotatable in the axis of rotation of said bolt, means for rotating said tumblers, a fence mounted for rotation about said axis and for sliding motion relatively thereto and said bolt, a spring pressing said fence toward said tumbler gatings, means deadlocking said fence against rotation when it is pressed against the peripheries of said tumblers and is outside the tumbler gatings, said means releasing said fence for rotation upon its movement into said tumbler gatings, and means locking said fence to said bolt when said fence is in said tumbler gatings.

10. In a lock of the class described, a rotatable bolt, a post extending in the axis of rotation of said bolt, a series of tumblers formed with gatings and rotatable about said post, means for rotating said tumblers, a fence mounted for rotation about said post and for sliding motion relatively thereto and said bolt, a spring pressing said fence toward said tumbler gatings, means deadlocking said fence against rotation when it is pressed against the peripheries of said tumblers and is outside the tumbler gatings, said means releasing said fence for rotation upon its movement into said tumbler gatings, and means locking said fence to said bolt when said fence is in said tumbler gatings.

11. In a lock of the class described, a rotatable bolt, a post extending from said bolt in the axis of rotation of said bolt, a series of tumblers formed with gatings and rotatable about said post, means for rotating said tumblers, a fence mounted for rotation about said post and for sliding motion relatively thereto and said bolt, a spring pressing said fence toward said tumbler gatings, means deadlocking said fence against rotation when it is pressed against the peripheries of said tumblers and is outside the tumbler gatings, said means releasing said fence for rotation upon its movement into said tumbler gatings, and means locking said fence to said bolt when said fence is in said tumbler gatings.

12. In a lock of the class described, a series of tumblers, a fence adapted to enter gatings formed in said tumblers, a spring pressing said fence into said gatings when said tumblers are aligned, means mounting said fence for rotation with said tumblers and for sliding movement relatively thereto into and out of said tumbler gatings, a pivoted disperser spring pressed into the path of said fence and rotatable out of the path of said fence by said fence as said fence rotates with said tumblers in one direction beyond said disperser, the return movement of said fence effecting contact of said fence with said disperser tending to rotate said disperser in a direction in which it resists rotation and thereby moves said fence out of the tumbler gatings.

13. In a lock of the class described, a series of tumblers, a fence adapted to enter gatings formed in said tumblers, a spring pressing said fence into said gatings when said tumblers are aligned, means mounting said fence for rotation with said tumblers and for sliding movement relatively thereto into and out of said tumbler gatings, a disperser positioned with a portion thereof in blocking relation to said fence when said fence is outside said tumbler gatings for preventing rotation of said fence, said fence moving beyond said disperser portion when in said tumbler gatings whereby to be rotatable thereafter past said disperser, said fence impinging against a further portion of said disperser as it rotates with said tumblers for depressing said portion, the return movement of said fence effecting contact of said fence with said disperser tending to move said disperser in a direction in which it resists movement and thereby moves said fence out of the tumbler gatings.

14. In a lock of the class described, a series of tumblers, a fence adapted to enter gatings formed in said tumblers, a spring pressing said fence into said gatings when said tumblers are aligned, means mounting said fence for rotation with said tumblers and for movement relatively thereto into and out of said tumbler gatings, and a disperser positioned with a portion thereof in

blocking relation to said fence when said fence is outside said tumbler gatings for preventing rotation of said fence, said fence moving beyond said disperser portion when in said tumbler gatings whereby to be rotatable thereafter past said disperser.

15. In a lock of the class described, a series of tumblers, a fence adapted to enter gatings formed in said tumblers, a spring pressing said fence into said gatings when said tumblers are aligned, means mounting said fence for rotation with said tumblers and for movement relatively thereto into and out of said tumbler gatings, and a disperser positioned with a portion thereof in blocking relation to said fence when said fence is outside said tumbler gatings for preventing rotation of said fence, said fence moving beyond said disperser portion when in said tumbler gatings whereby to be rotatable thereafter past said disperser, and means whereby said disperser moves said fence out of said gatings when said fence moves relatively to said disperser.

16. In a lock of the class described, a rotatable bolt, a post extending from said bolt in its axis of rotation, a series of tumblers mounted for rotation about said post, a dial for rotating said tumblers, a fence mounted for movement relatively to said bolt, means locking said bolt to said fence when said fence is moved to release position through the alignment of the gatings of said tumblers, said fence when out of said tumbler gatings allowing free rotation of said bolt relatively thereto, and key operated means for controlling the rotation of said bolt when said fence is out of said tumbler gatings.

17. In a lock of the class described, a rotatable bolt, a post extending from said bolt in its axis of rotation, a series of tumblers mounted for rotation about said post, a dial for rotating said tumblers, a fence mounted for movement relatively to said bolt, means locking said bolt to said fence when said fence is moved to release position through the alignment of the gatings of said tumblers, said fence when out of said tumbler gatings allowing free rotation of said bolt relatively thereto, and key operated means for coupling said bolt to said dial for rotation by said dial when said fence is out of said tumbler gatings.

18. In a lock of the class described, a rotatable bolt, a series of rotatable tumblers having gatings, a dial for rotating said tumblers to align said gatings, a fence adapted to enter said gatings when they are aligned, means whereby said fence when in said gatings is locked for rotation with said bolt, said fence when out of said gatings being free of said bolt whereby said bolt is then rotatable independently of said fence, and key operated means for controlling the rotation of said bolt when said fence is out of said tumbler gatings.

19. In a lock of the class described, a rotatable bolt, a series of rotatable tumblers having gatings, a dial for rotating said tumblers to align said gatings, a fence adapted to enter said gatings when they are aligned, means whereby said fence when in said gatings is locked for rotation with said bolt, said fence when out of said gatings being free of said bolt whereby said bolt is then rotatable independently of said fence, and key operated means for coupling said bolt to said dial for rotation by said dial when said fence is out of said tumbler gatings.

20. In a lock of the class described, a rotatable bolt, a post extending from said bolt in its axis of

rotation, a series of tumblers mounted for rotation about said post and having gatings, a dial for rotating said tumblers, a fence mounted for movement relatively to said bolt into and out of said gatings, means locking said bolt to said fence when said fence is moved to release position through the alignment of the gatings of said tumblers, said fence when out of said tumbler gatings allowing free rotation of said bolt relatively thereto, means for locking said fence against rotation when it is positioned out of said gatings, and key operated means for coupling said bolt to said dial for rotation by said dial when said fence is out of said tumbler gatings.

21. In a lock of the class described, a rotatable bolt, a post extending from said bolt in the axis of rotation of said bolt, a series of tumblers formed with gatings and rotatable about said post, a dial for rotating said tumblers, a fence mounted for rotation about said post and for sliding motion relatively thereto and said bolt, a spring pressing said fence toward said tumbler gatings, means deadlocking said fence against rotation when it is pressed against the peripheries of said tumblers and is outside the tumbler gatings while leaving said bolt free for rotation, said means releasing said fence for rotation upon its movement into said tumbler gatings, means locking said fence to said bolt when said fence is in said tumbler gatings, and key operated means for coupling said bolt to said dial for rotation by said dial when said fence is out of said tumbler gatings.

22. In a lock of the class described, a cylindrical casing, a shackle having legs slideable relatively to said casing, a bolt rotatable in said casing about an axis central of said casing, a post extending from said bolt in its axis of rotation, and a torsion spring secured between said post and casing for rotating said bolt into its locked position.

23. In a lock of the class described, a series of tumblers, a fence adapted to enter gatings formed in said tumblers, a spring pressing said fence into said gatings when said tumblers are aligned, means mounting said fence for rotation with said tumblers and for movement relatively thereto into and out of said tumbler gatings, a movable disperser spring pressed into the path of said fence and movable out of the path of said fence by said fence against the pressure of the disperser

spring as said fence rotates with said tumblers in one direction beyond said disperser, the return movement of said fence effecting contact of said fence with a cam surface of said disperser tending to move said disperser in a direction in which it resists movement and thereby moves said fence out of the tumbler gatings.

24. In a lock of the class described, a cylindrical casing, a shackle having legs slideable relatively to said casing, a bolt rotatable in said casing about an axis central of said casing, a part of said bolt adapted to lock said shackle, a post extending from said bolt in its axis of rotation, and a torsion spring secured between said post and casing for rotating said bolt into its locked position.

25. In a lock of the class described, a casing, a shackle slideable in said casing, a bolt rotatable in said casing for locking said shackle, a spring pressing said bolt into a locking position, a series of rotatable tumblers having gatings, a knob for rotating said tumblers to align said gatings, a fence spring pressed toward said gatings whereby to enter said gatings when they are aligned, means whereby said fence when in said gatings is locked for rotation with said bolt, means on said casing for locking said fence against rotation when said fence is positioned out of said gatings, said fence when in said gatings rotating with said tumblers and knob to move said bolt to release said shackle.

26. In a lock of the class described, a casing, a shackle slideable in said casing, a bolt rotatable in said casing for locking said shackle, a spring pressing said bolt into a locking position, a series of rotatable tumblers having gatings, a knob for rotating said tumblers to align said gatings, a fence spring pressed toward said gatings whereby to enter said gatings when they are aligned, means whereby said fence when in said gatings is locked for rotation with said bolt, means on said casing for locking said fence against rotation when said fence is positioned out of said gatings, said fence when in said gatings rotating with said tumblers and knob to move said bolt to release said shackle, and a portion of said fence locking means constituting a disperser for moving said fence out of said tumbler gatings as said bolt and fence move from an unlocking position back to a locking position.

FREDERIC K. HEYER.
